HANDLE FOR ARCHERY BOW

Robert M. Gray, South Bend, Ind., assignor to Plas-Steel Products, Inc., Walkerton, Ind., a corporation of Indiana

Filed Aug. 15, 1969, Ser. No. 18,699

Term of patent 14 years

Int. Cl. D22—02

U.S. Cl. D22—5

FIG.1

FIG.2

FIG.3

FIG.6

FIG.4

FIG.5

FIG. 1 is a view of the back of the handle for an archery bow showing my new design;

FIG. 2 is a view of the belly thereof;

FIG. 3 is a view of one side thereof, the other side being a mirror-image of the side shown;

FIG. 4 is a top plan view thereof;

FIG. 5 is a bottom view thereof;

FIG. 6 is a perspective view thereof on a reduced scale, the limbs and string of the bow being shown in broken lines for illustrative purposes only.

I claim:

The ornamental design for a handle for archery bow, as shown and described.
